QUINTIN PARKER, OF NEW YORK, N. Y.

Letters Patent No. 81,937, dated September 8, 1868.

IMPROVEMENT IN STEAM-GENERATORS.

The Schedule referred to in these Letters Patent and making part of the same.

TO ALL WHOM IT MAY CONCERN:

Be it known that I, QUINTIN PARKER, of the city, county, and State of New York, have invented a new and improved Locomotive-Boiler; and I do hereby declare the following to be a full, clear, and exact description thereof, which will enable others skilled in the art to make and use the same, reference being had to the accompanying drawings, forming a part of this specification.

Figure 1 represents a longitudinal section of my improved steam-boiler.

Figure 2 is a horizontal section of the same, taken on the plane of the line $z z$, fig. 1.

Figures 3, 4, and 5 are detail longitudinal sections of boilers now in use.

Similar letters of reference indicate corresponding parts.

This invention relates to a new construction of locomotive-boilers, and its object is to produce a boiler in which the lower flues cannot be clogged by cinders and ashes.

The invention consists chiefly in a discharge-channel, through which the ashes, cinders, and other impurities can, from the inclined plate in the rear of the flue-sheet, fall to the ground, or into the ash-pan, so that thereby the lower flues are kept clear from obstruction.

A, in the drawing, represents the shell of a locomotive-boiler.

B is the furnace-top.

C, the grate.

D, the flue-sheet.

The lower end of the flue-sheet is, by means of an inclined U-shaped plate, E, connected with the front plate a of the furnace.

It will be seen that the front end of the lower arm b of this plate E is in line with the bottom plate c of the shell A.

G is a channel or discharge-pipe, extending downward from the lowermost and front part of the upper arm d of the plate E. The pipe G passes through the lower part of the shell A for this purpose.

The upper end of the pipe G may be bifurcated.

The flame will, from the grate, pass up over the plate E, and then forward into the flues H, that project from the flue-sheet. Any cinders or ashes carried by the flame over the rear bend of the plate E, will be discharged again through the pipe G, and, besides this, a small, convenient fireplace is produced.

Heretofore boiler-furnaces were at first made square, but, when it was found that thereby the flame would be directed upward, and burn the flue-sheet and the front ends of the flues, a forward extension was provided, as in fig. 3.

This, however, was not profitable, as the fireplace became so large as to consume too large a quantity of fuel.

To improve this, the deflector was introduced, as in fig. 4, or the split furnace, as in fig. 5.

In either of these cases, the inclined backward extension would serve as a convenient support for ashes, cinders, &c., carried up by the flame, and by them the lower flues soon became stopped up.

The deflectors here shown were all too low, their upper plates being in line with the bottom of the shell.

The front part of the fireplace thus becomes too low.

It will be noticed that the upper arm d of my inclined extension E, reaches in front of the front plate of the furnace, and that the flue-sheet is also somewhat set forward, so as to allow the application of the pipe G in front of the furnace, as shown.

The pipe G also serves to carry fresh air into the boiler, to improve combustion.

I do not claim the arrangement of the deflector E, nor its use as a water-chamber.

Having thus described my invention, what I claim as new, and desire to secure by Letters Patent, is—

The combination of the pipe G with the boiler-sheet A, suspended from the upper plate of the deflector E, in rear of the flue-sheet, substantially as herein shown and described.

QUINTIN PARKER.
